(74) Attorney, Agent, or Firm—Mitchell P. Brook; Luce, Forward, Hamilton & Scripps LLP

(57) CLAIM

The ornamental design for a chair, as shown and described.

DESCRIPTION

FIG. 1 is a front perspective view of my new chair design;
FIG. 2 is a front elevation view of the embodiment of FIG. 1;

FIG. 3 is a left, side elevation view of the embodiment of FIG. 1, with the right side elevational view being a mirror image thereof;

FIG. 4 is a rear elevation view of the embodiment of FIG. 1;

FIG. 5 is a front elevation view of the embodiment of FIG. 1, without the chair arms. The arms of the chair in FIG. 5 have been omitted for convenience of illustration; and,
FIG. 6 is a top view of the embodiment of FIG. 1.

The broken line disclosure is for illustrative purposes only and forms no part of the claimed design.

1 Claim, 4 Drawing Sheets
